ADVERTISING SIGN

Frank E. Schmidt, Tigard, Oreg.

Application December 11, 1936, Serial No. 115,292

5 Claims. (Cl. 40—32)

My invention is comprised of a case having its bottom hinged to facilitate the replacement, adjustment and positioning of endless and delineated bands or belts, that are disposed therein. 5 A prime mover is disposed within the case and drives are disposed between the prime mover and the shafts about which the endless delineated bands or belts are trained. Transparent fronts are provided for the case in order that the sign 10 may be viewed from each of its broad faces simultaneously.

The primary purpose and object of my invention is to provide a continuously moving sign that may be seen from its opposite sides with equal 15 facility and one that may be easily replaced with an additional sign without in any way altering or affecting the component elements comprising the sign itself.

A further object of my invention is to provide 20 a sign that will be comprised of a minimum number of parts and one that may be used over long periods with practical freedom from operating mechanical annoyances.

I am aware that signs of the flasher type and 25 of the fixed type have been provided but I am not aware that signs of the type hereinafter to be described have heretofore been used and developed.

Through the use of my new and improved device 30 it is now possible to have a plurality of delineated bands or belts carrying advertising indicia that may be placed within the sign and used for a period of time and thereafter be replaced with other signs without in any way altering 35 the sign structure, it being possible to change one of the delineated belts with another with a minimum stoppage of the sign and with a minimum of delay.

A further object of my invention consists in 40 providing a sign having delineated bands or belts disposed therein, each of which may be driven in an opposite direction to thereby create additional optical illusion in the operation of the sign.

With these and incidental objects in view, the 45 invention consists in certain novel features of construction and combination of parts, the essential elements of which are set forth in the appended claims, and a preferred form of embodiment of which is hereinafter shown with reference 50 to the drawings which accompany and form a part of this specification.

In the drawings:

Fig. 1 is a front view of the assembled sign 55 shown erected in place.

Fig. 2 is a fragmentary partially sectional front view of the driven end of the assembled device.

Fig. 3 is a fragmentary partially sectional front view of the driving end of the assembled device.

Fig. 4 is a fragmentary sectional inverted plan 5 view of the driven rollers and the associated elements. This view is taken on line 4—4 of Fig. 2, looking in the direction indicated.

Fig. 5 is a fragmentary sectional end view of the supporting frame of the driven end. This 10 view is taken on line 5—5 of Fig. 2, looking in the direction indicated.

Fig. 6 is a fragmentary plan view of the drive and the train of gears associated therewith. This view is taken on line 6—6 of Fig. 3, looking in 15 the direction indicated.

Fig. 7 is an end view of one end of the driven roller and a fragmentary partially sectional plan view of the support for the same. This view is made to illustrate the compressible cushion member disposed therein, the position of which is to maintain the delineated endless driving bands or belts in a suitably taut condition. 20

Fig. 8 is a front view of the instrumentalities used for supporting and driving the delineated 25 endless belts or bands.

Like reference characters refer to like parts throughout the several views.

1 is the case of the assembled device. The case is preferably a double faced case in order that 30 the sign may be viewed from its broad front and back surfaces with equal facility. The bottom 2 of the case is so arranged as to facilitate its being hinged downward for inspection and adjustment of the parts disposed therein. 35

I provide a sub-frame 3 disposed within the case to which the driving and driven assembly and the prime mover may be attached and secured and which is adapted for having the same 40 attached thereto in advance of the same being secured and placed within the case.

I provide a plurality of driving drums 4 and 5, here shown as two in number, but I do not wish to be limited to two as a different number may be 45 used with equal facility.

The driving drums 4 and 5 have driving elements as gears 6 and 7 associated at one of their ends. The gears 6 and 7 are adapted for coacting with each other.

A prime mover as an electric motor 8 is placed 50 within the frame 3 and the prime mover has journal bearings 9 and 10 associated therewith into which a shaft 11 is journaled. The shaft 11 passes through a gear box 10A. The motor leads are shown at 12. The shaft 11 is driven by means 55

of reduction gears, not here shown, from the armature shaft of the prime mover 8. A suitable driving gear 13 is mounted upon the shaft 11 and the same coacts with and drives the gear 7 and in turn the gear 6, to thereby impart rotation to the respective driving drums 4 and 5. A driving sprocket 14 is associated with the shaft upon which the drum 4 is mounted. A stub shaft 15 is secured to the frame 3 and a sprocket 16 is secured to the stub shaft 15 and a driving element as a chain 17 is trained about the respective sprockets 14 and 15 and drives the same. A bevel gear is also mounted upon the stub shaft 15 and the same coacts with and drives a bevel gear 19.

15 The driving drum 5 and a driven drum 20 are companion drums and a delineated endless belt or band 21 is trained about the lower enlarged end of the respective companion drums 5 and 20. A driven drum 22 is a companion drum to the driving drum 4 and a delineated endless belt or band 21 is trained about the respective companion drums 4 and 22. To prevent the band 21 from creeping down the drums I place a strip 21A on the inside of the top of the band 21. The respective drums 4, 5, 20 and 22 are mounted upon shafts that are journaled on their upper ends relative to the frame 3 and drums 4 and 5 are driving drums and drums 20 and 22 are driven drums. In order that the delineated belts or bands may be freely changed relative to the respective drums upon which the same are wound I have found it necessary to have access to one end of the respective drums and I have found it desirable to make this accessible to the lower end of the drum.

30 35 This is particularly desirable where the same is being used for outdoor display and where the sign is hung in spaced relation with the supporting structure.

To make this easily accessible I hinge the bottom wall 2 of the case downward about the hinge pin 24. The bottom 2 has a bracket 26 disposed upon its free end and a hole 27 is disposed therein. A locking pin 28 is used for fastening the bottom wall 2 in raised, closed position. Journal bearings 29, 30, 31 and 32 are disposed upon the lower end of the shafts upon which the respective drums 4, 5, 20 and 22 are mounted and anti-friction bearings 33, 34, 35 and 36 are provided for the respective shafts. The anti-friction bearings are mounted within suitable supports 37 and 38. Supports 37 and 38 are hinged respectively to the supports to facilitate the anti-friction bearings being placed into and out of registry with and in engagement with the journal bearings 29 to 32 respectively. This is made necessary because of the frequent changing of the endless belts or bands that are to be placed about the respective pairs of drums 4 and 22, 5 and 20. The bearing support 38 is hingedly secured to a yoke 39. The yoke 39 is adjustable relative to the case 3 by any adjusting means as by set screws 40 and 41. The purpose of providing the yoke 39 is to provide means for maintaining the belts or bands in a relatively taut condition after the same have been placed upon the respective pairs of drums. In order that the two pairs of drums may be independently adjusted I provide supporting channel ways 42 as illustrated in Figs. 4 and 5 and each of the housing supports 50 has bolts 50A disposed therein and has a supporting bolt 44 secured thereto and the head 45 of the same moves within the channel way 46 that is disposed within the channel member 42. An elongated slot 47 is disposed within each of the journal supports 48 and a set screw 49 locks the journal supports 48 relative to the journal support 50. This provides independent adjusting means to adjust one pair of rollers relative to the other.

It will be noted that the driving drum 50 is rotated in one direction and the driving drum 4 is operated in the opposite direction. This provides means for driving the delineated band 21 in one direction and the delineated endless driving band or belt 23 in the opposite direction. It will be noted that I also place an inner band 23A on the inside and adjacent the top edge of the band 23 to prevent the band from creeping along the drums. Both of the bands 23 and 21 are made wider than the surface of the drums upon which it is operated to permit the inner bands 21A and 15 23A riding the top end of each of the drums.

While it is believed fundamental that these driving belts or bands should be driven at all times in opposite directions by placing a single additional pinion between the shafts 29 and 30 20 they could be driven in the same direction with equal facility. By driving the same in the opposite directions the apparent difference in speed will be double what it would be if they were driven in the same direction.

To provide facilities for furnishing a delineated endless band or belt that will run inclined to the horizontal and disappear below and above the respective horizontal lines of the respective bands 21 and 23 I provide a frame 51 between 30 the shafts 30 and 31. The drums disposed thereupon operate the same between the bands 21 and 23 and secure the same to the frame 3 by any suitable fastening means as by clamp screws, as illustrated at 52.

I suitably mount a driving drum 53 at one end of the frame 51 and a driven drum 54 at the opposite end of the frame. The shaft 55 upon which the drum 53 is mounted has the bevel gear 19 mounted thereupon. This effects driving relationship between the drum 53 and the prime mover 8. An adjustable relationship may be developed between the driving drum 53 and the driven drum 54 by placing adjusting screws 56 and 57 between the respective frames upon which the driving and driven drums 53 and 54 are mounted. The screws 56 and 57 are right and left hand screws respectively. A hand threaded member 58 is secured to the respective screws to impart adjusting movement to the respective frames upon which the driving and driven drums are mounted.

In Fig. 1 I have shown one of my new and improved signs being supported upon a wall 59. The same is secured thereto by suitable supporting brackets 60 and 61 and the same is suspended in place by any suitable cable 62.

In order to further enhance the optical illusion that is developed through the use of my device I provide suitable props 63 and 64 at the oppositely disposed ends of the display. These props are removably placed within the sign case and may be removed and replaced by others more suitable to the sign being displayed.

It will be noted that a motor bus 65 is delineated upon the belt 21, that a skyscape shown by clouds 66 are mounted upon the delineated endless belt or band 23 and that an airplane 67 is delineated upon the endless band or belt 68 that is trained about the respective driving and driven drums 53 and 54.

It will also be noted that the endless band or belt may be freely placed upon and removed from the driving and driven drums 53 and 54.

The props 63 and 64 are positioned in front 75

of and cover the return position about which the endless delineated bands or belts turn to thereby increase the optical effect produced by the sign herein described.

5 I place a plurality of electric light bulbs 69 within the case and position the same so that they will illuminate, if desired, the transparency of the endless delineated power driven bands and the outside of the same to produce desired and 10 essential lighting effects and to enhance the optical illusion that may be created by the sign when in operation.

In order that the supports for the bearings 33, 34, 35 and 36 may be held in place and be positioned with little effort I provide supporting links 15 70 and 71 and position the same so that the supports 31 and 38 may be placed in registry alignment therewith. The links 70 and 71 are hinged relative to the case by hinge pins 72 and 73. The 20 hinge pins are supported within suitable brackets that are secured to the case 1.

Locking screws 74 and 75 are associated with the links which are made to pass through slots that are disposed within the swinging ends of 25 each of the supports 37 and 38.

It is highly desirable that the endless delineated belts or bands be maintained in a suitable taut condition during their operation. It is also quite essential that the same operate against a 30 cushion to compensate for any stretch that may develop within the bands or belts. To accomplish this I provide an elongated socket 76 within each of the supports for each of the bearings that support the driven drums and I place a 35 shoe 77 within the socket that engages the outside of the respective bearings and a spring or other cushioning device 78 maintains the shoe 77 in intimate contact within the outer surface of the bearings.

40 While I have shown only one prime mover such as motor 8, my device may be operated equally as well with an individual motor upon each pair of rollers which may be independently operated.

While the form of mechanism herein shown 45 and described is admirably adapted to fulfill the objects primarily stated, it is to be understood that it is not intended to confine the invention to the embodiment herein shown and described, as it is susceptible of embodiment in various 50 forms, all coming within the scope of the claims which follow.

What I claim is:

1. In a device of the class described, the combination of a case, a sub-frame disposed within 55 the case with one end of the sub-frame being adjustable relative to the case, pairs of driving and driven drums disposed within the case, bearings for each end of the respective driving and driven drums, with the bearings for one end of 60 the respective drums being adapted for being placed into and out of registry with the bearing end of the respective drums, delineated endless bands trained about the respective pairs of driving and driven drums, with the said delineated 65 endless bands being wider than that portion of the drums upon which the same rides, a band disposed adjacent the top edge and disposed upon the inner side of each of the delineated

endless bands, power means for driving the driving drums and a plurality of props disposed within each case and said props being placed adjacent the driving and driven drums and positioned to hide the point of wrap of the delineated 5 endless bands about the respective driving and driven drums.

2. In a device of the class described, the combination of a case, means for supporting the case and for illuminating the same from within, a 10 sub-frame disposed within the case, means for hinging the bottom of the case to afford entry to within the case, a plurality of pairs of driving and driven elements disposed within the case and mounted relative to the sub-frame, endless delineated bands trained about the pairs of driving and driven elements, means mounted upon the endless delineated bands for preventing the same creeping the respective drums about which the same are trained, means for simultaneously driving the endless delineated bands in opposite directions, and a plurality of props placeable within the case and adjacent the ends of the case. 15

20 3. In a device of the class described, the combination of a case, means for supporting the case, a plurality of power driven endless delineated bands disposed within the case, means for illuminating the surfaces of each of the delineated bands that are exposed to view at either side of the case, means for driving and supporting the delineated bands in opposite directions, means preventing the creeping of the bands relative to the supports about which the same are trained, and props disposed within the case and placed between the inner broad surface of the case and the outside of the endless bands and means facilitating the changing of the bands relative to the driving and supporting elements about which the same are trained. 25

30 4. In a device of the class described, the combination of a case, a frame disposed within the case, a plurality of pairs of driving and driven drums adjustably supported within the frame, an endless delineated belt trained about each of the pairs of drums and an endless band secured 40 to the delineated belt for maintaining the belts upon the respective drums and for preventing the same crawling therealong, means for adjusting the spaced relationship between the driving and driven drums of each pair of the respective drums, means for illuminating the delineated endless belts and a plurality of props removably disposed within the case. 45

5. In a device of the class described, the combination of a case, a plurality of endless delineated bands rotatably mounted within the case, some of said bands being adapted for being driven in horizontal movement and other of said bands being adapted for being driven in a path inclined to the horizontal, power means for simultaneously driving the delineated bands in predetermined directional movement, means for illuminating the delineated bands from opposite sides and a plurality of props disposed within the case and disposed between the broad surfaces of the case and the endless delineated bands disposed therein. 55 60 65

FRANK E. SCHMIDT.
